Filed Aug. 14, 1972, Ser. No. 280,496

Term of patent 14 years

Int. Cl. D30—99
U.S. Cl. D30—99

FIG. 1 is a front elevational view of an animal toilet, showing my new design;

FIG. 2 is a right side elevational view, the left side being substantially a mirror image thereof;

FIG. 3 is a rear elevational view;

FIG. 4 is a top plan view;

FIG. 5 is a bottom plan view;

FIG. 6 is a cross-sectional view, partly in top plan, taken along line 6—6 in FIG. 1, the paddle and chain being omitted for convenience in illustration; and

FIG. 7 is a cross-sectional view, partly in side elevation, taken along line 7—7 in FIG. 4.

I claim:

The ornamental design for an animal toilet, as shown.
